COOKING TOP UNIT

Ray C. Sandin, Northbrook, Ill., assignor to General Electric Company, a corporation of New York

Application May 13, 1954, Serial No. 30,459

Term of patent 14 years

(Cl. D81—25)

To all whom it may concern:

Be it known that I, Ray C. Sandin, a citizen of the United States, residing at Northbrook, in the county of Cook and State of Illinois, have invented a new, original, and ornamental Design for a Cooking Top Unit, of which the following is a specification reference being had to the accompanying drawing, forming a part thereof.

Fig. 1 is a plan view of a cooking top unit showing my new design.

Fig. 2 is a sectional view thereof taken on line 2—2 of Fig. 1 and looking in the direction of the arrows.

The design for the cooking top unit disclosed is characterized by the trapezoidal pattern of the burners, the trapezoidal control panel and the trapezoidal pattern of the knobs on the panel, as shown.

I claim:

The ornamental design for a cooking top unit, substantially as shown and described.
